UNITED STATES PATENT OFFICE.

ASBURY BURNETT, OF BIG SPRINGS, KANSAS.

WASHING-MACHINE.

SPECIFICATION forming part of Letters Patent No. 374,141, dated November 29, 1887.

Application filed February 12, 1887. Serial No. 227,389. (Model.)

To all whom it may concern:

Be it known that I, ASBURY BURNETT, a citizen of the United States of America, residing at Big Springs, in the county of Douglas 5 and State of Kansas, have invented certain new and useful Improvements in Washing-Machines, of which the following is a specification, reference being had therein to the accompanying drawings.

10 This invention pertains to certain new and useful improvements in washing-machines; and it consists in the detailed construction, combination, and arrangement of the parts, substantially as hereinafter fully set forth, and 15 particularly pointed out in the claims.

In the accompanying drawings, Figure 1 is a plan view of my invention. Fig. 2 is a cross-sectional view thereof on the line $x-x$, Fig. 1; and Fig. 3 is a detail view with parts broken 20 away.

In carrying out my invention I employ a preferably oblong tub or receptacle, A, which is provided on either side with upright bars a , slotted in their upper ends, as at a' , into 25 which open slots or recesses a'' , formed in the sides of the tub or receptacle, as shown. These upright bars are grooved on the inner surfaces of their opposite sides, wherein slide shaft bearing plates or blocks b , the outwardly-projecting 30 lips of which slide in said grooves, as shown in Fig. 1. These plates or blocks have the upper ends of coil-springs b' secured thereto, the lower ends of said springs bearing in the ends of the slots a' of the upright bars a .

35 B is a horizontally-disposed shaft, the narrowed ends of which rest upon the bearing plates or blocks b , and said shaft has secured between apertured lugs or protuberances b^2 on its upper surface a frictional roll, C, the purpose of which will appear further on. To this shaft are secured two downwardly-projecting bars or rods, C', which are connected at their lower ends to an ordinary rubber, D. Two outwardly-projecting normally horizontally-disposed bars, $d d$, are likewise secured to said 40 shaft and to a cross-bar, d' , the ends of which cross-bar have secured thereto the upper outer ends of suitable inclined bars, which are also secured to the rubber D, the whole comprising 45 the operating-handle.

In the bottom of the tub or receptacle are

secured, in any suitable manner, a series of revolving wooden rollers, E, the narrowed shaft-like ends of which bear in grooves formed in the connecting-pieces, as customary. 55

Midway between the shaft B and a circular cross-piece, e , is secured a strong coil-spring, F, the ends of which are secured in apertured bolts f , working in the sides of the tub or receptacle, whereby the tension of the spring 60 may be regulated as may be desired.

G is a removable pressure-bar, which is designed to be placed in under the coil-spring F, and to rest at one end on the upper surface of the cross-piece e and the other end upon 65 the frictional roll C on the shaft B. It is obvious that this arrangement will have the effect of causing the removable pressure-bar to bear down upon the shaft B, against the action of the coil-springs of the shaft bearing plates 70 or blocks, and in practice, when heavy or cumbersome clothes are undergoing the washing operation, the passage of the same between the revolving rollers E and the rubber D will be readily permitted by raising the outer end 75 of the pressure-bar against the action of the spring F. By moving the operating-handle the washing of the clothes will of course be accomplished in the usual manner. When it is desired to loosen or tighten the tension of 80 the spring F, the same is effected through the agency of the apertured bolts f , to which the ends of said spring are connected, as before stated.

Having thus fully described my invention, 85 what I claim, and desire to secure by Letters Patent, is—

1. The combination, with the tub or receptacle, the shaft, and the rubber, of the spring, the circular cross-piece, and the removable 90 pressure-bar disposed in under said spring and bearing on said shaft and cross-piece, all arranged substantially as shown and described.

2. The combination, with the tub or receptacle and the rubber, of the shaft, the frictional roll, the spring, the cross-piece, and the pressure-bar bearing on said cross-piece and roll, substantially as shown and described. 95

3. The combination, with the tub or receptacle and the slotted bars, of the shaft, the spring-held bearing plates or blocks, the 100

spring, the circular cross-piece, and the pressure-bar, substantially as shown and described.

4. The combination, with the tub or receptacle, the slotted bars, the spring-held bearing plates or blocks having lips sliding in grooves of said bars, and the circular cross-piece, of the shaft, the frictional roll, the spring, the pressure-bar, the rubber secured by bars to said shaft, and the operating han-

dle, all arranged substantially as shown and so described.

In testimony whereof I affix my signature in presence of two witnesses.

ASBURY BURNETT.
